A. M. DEMUTH
COOKING APPARATUS

Filed April 14, 1923

FIG. 3

Inventor
Alfred M. Demuth
By. *John J. Gately, Jr.*

UNITED STATES PATENT OFFICE.

ALFRED M. DEMUTH, OF CHICAGO, ILLINOIS.

COOKING APPARATUS.

Application filed April 14, 1923. Serial No. 632,036.

To all whom it may concern:

Be it known that I, ALFRED M. DEMUTH, a citizen of the United States, residing at Chicago, in the county of Cook and State of Illinois, have invented certain new and useful Improvements in Cooking Apparatus, of which the following is a specification.

In cooking apparatus of the character embodying a hermetically sealed cooking chamber in which the articles of food are cooked by pressure of the steam or vapor generated within the chamber, it is necessary to provide fastening devices for the cover or closure to prevent the same from being displaced by the pressure within the chamber.

The fastening devices heretofore employed embody wing nuts carried upon bolts or screws pivotally connected with the wall of the chamber. After the nuts have been adjusted to secure the closure in position and after the cooking operation has proceeded for a short time, the nuts and bolts become very hot, causing the parts to swell and to bind upon each other, with the result that it is very difficult to loosen them for the purpose of removing the closure. Oftentimes it is necessary to employ an implement for that purpose and in many instances the hands of the operator have become badly burned. Furthermore it has heretofore been necessary to place the cover upon the vessel in a particular position before the securing means can be operated or adjusted.

It is one of the objects of the present invention to provide an improved fastening means for the closure, which may be readily adjusted under all conditions and thereby permit the closure to be readily and quickly removed, without necessitating the use of an implement and also obviating the danger of the operator burning his hands, at the same time provide an improved closure which may be placed upon the vessel in any position, the fastening means being operative in any position of the closure upon the vessel.

A further object is to provide an improved construction of bottom which will protect the contents of the vessel and which

will also not interfere with nor impair or retard the cooking operation.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which—

Figure 1 is a side elevation of an improved apparatus of this character constructed in accordance with the principles of this invention with parts broken away.

Figure 2 is a top plan view of Figure 1.

Figure 3 is an enlarged detail plan of a portion of the supplemental bottom.

Referring more particularly to the drawing the numeral 10 designates generally a cooking vessel, which may be of any desired size and configuration and constructed of any suitable material. Arranged beneath the bottom 11 of the receptacle and spaced therefrom is a supplemental bottom 12, which may be constructed of any suitable material and is so shaped that there will be provided a dead air space 13 between the bottom 11 and the supplemental bottom 12. This may be accomplished in any suitable manner but preferably by means of a flange 14, which encompasses the supplemental bottom 12, and projects for the desired distance thereabove. When in position the free edge of the flange 14 abuts the lower face of the bottom 12 to hold the supplemental bottom spaced from the bottom 11. This supplemental bottom 12 may be secured in position in any suitable manner preferably by means of suitable fastening devices 15, which pass through a flanged portion 16 projecting below the bottom of the vessel. These fastening devices 15 are preferably in the form of screws which enter threaded apertures 17 opening through the outer face of the flange 14, and in order to provide sufficient material or stock in which the threaded recesses 17 are formed, lugs or projections 18 may be formed on the inner face of the flange 14.

The vessel 10 is open and encompassing

the upper end thereof is a flange 19, the outer face 20 of which is beveled or inclined. One edge of the inclined portion 20 is substantially flush with the upper end 5 of the wall of the vessel 10 and extends outwardly and downwardly therefrom and terminates short of the base of the flange 19 to form a circumferential shoulder 21.

The vessel is provided with a detached 10 closure 22 of any desired configuration and is provided with an internal inclined face 23 adapted to engage and rest upon the inclined or beveled surface 20 of the vessel. A flange 24 may also be provided on the closure 22 15 to encompass the flange 19 and this flange 24 co-operating with the shouldered portion 21 of the flange 19 serves as a means for positioning and guiding and locating the closure 22 in position.

20 The closure 22 is provided on its outer surface and adjacent the inclined surface 23 with a circumferentially disposed flat bearing surface or shoulder 25, which is continuous and extends completely around the closure. This surface 25 is disposed in 25 proximity to the inclined surface 20 of the flange 19 when the closure is in position. The inclined surface 20 on the vessel and the inclined surface 23 on the closure co-operate 30 to guide the closure in position.

The closure is secured in position and against accidental displacement by means of suitable clamps 26, one end of which projects between spaced ears 27 on the wall of 35 the vessel 10 and is pivotally connected thereto by means of a pivot pin 28 passing through the ears and through the end of the clamp member 26.

40 The other end 29 of the clamp member 26 is provided with screw threads therethrough which receives a screw or bolt 30. Carried by the end of the screw or bolt is a head 31 having a flat surface adapted to engage and rest upon the flat surface 25 45 of the closure. To the other end of the screw or bolt 30 is connected a handle 32 and the threads of the screw or bolt are of such a pitch that the member 30 will be quickly advanced or retracted with respect 50 to the end 29 of the clamp 26, when it is rotated by the handle 32.

55 Any desired number of these clamps or fastening devices may be provided and by the provision of the circumferential flat surface 25 upon which the member 31 rests, and the arrangement of the co-operating inclined surface 20 on the vessel 10 and the inclined surface 23 on the closure 22, it will be manifest that the closure may be placed 60 in position upon the vessel 10 in any desired position and rotated with respect thereto before the members 31 of the screws 30 are clamped against such surface. The clamp or fastening device 26 will be operative in any position of the closure upon the

vessel as a portion of the flat surface 25 on the closure will always be in a position to be engaged by clamps or fastening devices.

If desired the closure may be provided with a pressure gauge 33, an air vent 34, 70 and a safety blow off valve 35, all of any desired or well-known construction and which have communication with the interior of the vessel 10. Handles 36 may also be provided on the closure for lifting the same 75 and suitable handles 37 may be provided on the vessel by means of which the vessel may be transported.

By the provision of the inclined surfaces 20 and 23, which co-operate with each other 80 and by the provision of the screws or bolts 30, it will be manifest that the inclined surface 23 may be forced over the surface 20, so as to form a fluid tight joint between the closure and the vessel. When it is desired 85 to remove the closure for any purpose, the screws 30 may be quickly rotated by a slight movement of the handles 32, to release the closure without danger of burning the hands of the operator and without necessitating the use of any implement to rotate the screws.

90 It will be noted that the handles 32 are connected with the ends of the screws 30 by means of an enlarged head or ball 32^a and 95 that the screws or bolts have extended bearings in the ends 29 of the clamp members 26. This construction is provided not only for the purpose of providing weight at the end of the clamp and upon the screws, but 100 also insures that the screw or bolt will not bind in its bearing but will insure a quick and easy movement of the screw without twisting the clamp member.

105 While the preferred form of the invention has been herein shown and described, it is to be understood that various changes may be made in the details of construction and in the combination and arrangement of the several parts, within the scope of the 110 claim, without departing from the spirit of this invention.

115 What is claimed as new is:—

A cooking vessel, the periphery of the vessel encompassing the upper end thereof being inclined or beveled and having a laterally projecting circumferential flange at the base of the said inclined portion, a closure for the vessel, said closure extending over and encompassing said beveled or inclined portion and also the said circumferential flange, a portion of the inner face of the closure spaced from the edge thereof being inclined to engage and rest upon the said beveled or inclined surface of the receptacle, a portion of the outer surface of the closure directly above the said inclined portion thereof being shaped to form an encompassing flat surface spaced from the peripheral edge of the closure, a plurality of 120 125 130

clamping members pivoted to the receptacle and adapted to extend over the said flat surface of the closure, a screw threaded through each of the clamping members and having an enlarged flat surface on the end thereof to engage the said flat surface of the closure, and a handle connected with each

of the said screws for operating it and for swinging the said clamping members about their pivots.

In testimony whereof I have signed my name to this specification, on this 12th day of April, A. D. 1923.

ALFRED M. DEMUTH.
